(57) **CLAIM**

The ornamental design for a smart ring with charging base as shown and described.

DESCRIPTION

FIG. 1 is a top perspective view of a smart ring with charging base as shown and described;

FIG. 2 is a bottom perspective view of the smart ring with charging base.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a perspective view of the smart ring with charging base shown in a state of use.

The broken lines illustrate portions of the smart ring with charging base that form no part of the claimed design.

1 Claim, 9 Drawing Sheets
